SHUTTLE

Filed Oct. 24, 1928

UNITED STATES PATENT OFFICE

JOHN W. STEWARD, OF PATERSON, NEW JERSEY

SHUTTLE

Application filed October 24, 1928. Serial No. 314,598.

In loom shuttles of the type having spindles pivotally mounted so as to be raised for replenishing the weft supply there are usually two pairs of pins driven into the shuttle body, one acting to support and for limiting the pivotal movement of the spindle and the other to support the spring which is used to keep the spindle normally in the depressed position and usually acts, also, to hold the spindle in the elevated position when raised. The working out of these pins when the shuttle is in use and the weakening of the shuttle body by them are known serious faults characterizing shuttles of this type, and the principal object of this invention is therefore to eliminate these faults.

The drawing shows, in—

Fig. 1 a plan of the improved shuttle;

Fig. 2 a plan, with the shuttle body broken away to expose the spindle support and spring;

Figs. 3 and 4 sections each on line 3—3, Fig. 2, the spindle being depressed in Fig. 3 and raised in Fig. 4;

Fig. 5 a view similar to Fig. 2, with the spindle removed and the support shown dotted in the act of being removed;

Fig. 6 a section on line 6—6, Fig. 3, with the mounting and spindle removed;

Figs. 7 and 8 sections on lines 7—7 and 8—8, Fig. 3, with the spindle removed; and

Figs. 9 and 10 views of blanks of certain of the parts.

The shuttle body 1 has, open at top and bottom, the usual filling-package cavity 2, 3 being a wooden quill forming the core of the package, though a paper cop tube may of course be used.

The cavity has a mortise 4 open at the bottom but closed at the top by a wall 5 except where it adjoins the cavity, where it also is open at the top; the inner end of said wall forms an abutment 5^a. The mortise is enterable from the cavity by the hereinafter described support, and its bottom is formed by two lateral longitudinally extending and opposite ledges 6, 6^a (Fig. 3) being a cross-ledge at its outer end on which a part of said support, when entered, has a bearing, as will appear; at its inner end the mortise has two

opposite vertical notches 7, and leading to these from the exterior side surfaces of the body 1 are two reach holes 8.

From a stiff sheet metal blank 9 having the form shown in Fig. 9 a trough-shaped case, affording said support, is formed and this may have tongues 9^a thereof, forming at one end of the case the ends of its side walls, so bent as to produce hooks to engage (Fig. 1) in the usual circumferential groove shown at the butt of the quill 3, and the tongues 9^b, forming at the other end of the case the ends of its side walls, bent from each other to produce detents 10. The sides of this case are bridged by a pin or pivot 11, whose ends (here) terminate flush with the side surfaces of the case and may be upset or riveted. The case or support, may be slid into the mortise, which it snugly fits, having first pressed its tongues 9^b together, and it will then be held against return displacement by detents 10 engaging in the notches 7 into which, due to some elasticity present in the metal, they spring when the case is fully home in the mortise. Opposite and inwardly open longitudinal slots forming jaws 12 exist in the case at its bottom (Figs. 3, 4 and 9) because the lower edges of the tongues 9^b are somewhat above the plane of the top surface of the intermediate tongue 9^c.

The spindle spring is formed by bending the blank 13 in Fig. 10 into the shape shown in Fig. 3. Its wider end or head 13^a is entered into jaws 12, which it fits and which afford rigid means to support it, especially since the end of tongue 9^c rests at its end on ledge 6^a. The spring thus forms in effect an extension of the support, though it is detachable therefrom when the support is withdrawn from the mortise.

The spindle 14 is of the type having its butt formed as a hook 14^a, open upwardly, being adapted to receive pivot 11 and being engageable therewith or disengageable therefrom by hooking it thereon or unhooking it therefrom, as will be apparent. The spring bears at its free end against the surface 14^b of the spindle and tends to hold it depressed, while permitting it to be raised to the position of Fig. 4. In order to provide the

spindle butt with an adequate reach from its axis to the point 14° or heel thereof so that the spring may obtain a good purchase on the spindle when depressed and still permit the spindle to rise tongue 9° may be bent away and thus depressed at 9°, thus affording clearance for the spring end when the spindle is elevated (see Fig. 4).

My construction differs from others in its class in that, given a shuttle body having a mortise and a filling-package-carrying structure comprising a spindle pivoted at its butt on a transverse axis and a support for the spindle in which the same is pivoted, said support while said structure is so constituted is shiftable in the mortise and said body and support have a spring-interlock (9b-7) normally opposing such shifting of the support. My construction further differs in that, given a shuttle body having a mortise and a filling-package-carrying structure comprising a spindle pivoted at its butt on a transverse axis and a support for the spindle in which the same is pivoted and having spring means engaging the spindle and yieldingly retaining the latter at a definite point in its range of movement, said support while said structure is so constituted is shiftable in the mortise and said body and support have a releasable interlock normally opposing said shifting. Thus three of the pins commonly used in this type of shuttle are eliminated and it is even possible to mount the fourth pin or spindle pivot so that holes 35 in the shuttle body to receive the same are unnecessary, wherefore the pin cannot work out and the shuttle body is not weakened. The removal of said structure may be accomplished by entering suitable means at reach holes 8 for releasing the detents 10.

The spindle may be independently detached by first raising it to the position shown by full lines in Fig. 4 and then, utilizing the end of wall 5 as a fulcrum, forcing it to the dotted line position so that it clears the pin.

Having thus fully described my invention, what I claim is:

1. In combination, a shuttle body having a mortise and a filling-package-carrying structure comprising a spindle pivoted at its butt on a transverse axis and a support for the spindle in which the latter is pivoted, said support while said structure is so constituted being shiftable in the mortise and said body and support having a spring-interlock normally opposing such shifting of the support.

2. In combination, a shuttle body having a mortise and a filling-package-carrying structure comprising a spindle pivoted at its butt on a transverse axis and a support for the spindle in which the latter is pivoted, said support while said structure is so constituted being shiftable in the mortise and said

support having elastic means engaged with said body and normally opposing such shifting of the support.

3. In combination, a shuttle body having a mortise and a filling-package-carrying structure comprising a spindle pivoted at its butt on a transverse axis and a support for the spindle having spaced members in and between which the spindle is pivoted, said support while said structure is so constituted being shiftable in the mortise and having one of said members elastic and engaged with said body and normally opposing such shifting of the support.

4. In combination, a shuttle body having a mortise and a filling-package-carrying structure comprising a spindle pivoted at its butt on a transverse axis and a support for the spindle in which the latter is pivoted having rigidly connected therewith spring means engaging the spindle and yieldingly retaining it at a definite point in its range of pivotal movement, said structure while so constituted being shiftable in the mortise and said structure and body having portions thereof forming a releasable interlock normally opposing such shifting of said structure.

5. In combination, a shuttle body having a mortise and a filling-package-carrying structure comprising a spindle pivoted at its butt on a transverse axis and a support for the spindle in which the latter is pivoted having spring means engaging the spindle and yieldingly retaining it at a definite point in its range of pivotal movement, said support while said structure is so constituted being shiftable in the mortise and said body and support having a spring-interlock normally opposing such shifting of the support.

6. In combination, a shuttle body having a mortise, a sheet-metal support slid into the mortise and comprising spaced side walls and a portion stiffly connecting them, and a spindle pivoted at its butt on an axis penetrating said walls and transverse to the butt, said walls having elastic gripping portions yieldingly engaged with said body in the mortise and holding the support against shifting therein.

7. In combination, a shuttle body having a mortise, a sheet-metal support slid into the mortise and comprising spaced side walls and a portion stiffly connecting them and also an elastic extension extending between said walls, and a spindle pivoted at its butt on an axis penetrating said walls and transverse to the butt and having said extension bearing thereagainst and normally holding the spindle at a definite point in its range of movement, said walls having elastic gripping portions yieldingly engaged with said body in the mortise and holding the support against shifting therein.

8. In combination, the fixed structure of a

shuttle, a spindle pivoted at its butt on a transverse axis in said structure, and a plate spring engaging the spindle and yieldingly retaining it at a definite point in its range of movement, said structure having a slot substantially equaling in width the thickness of the spring and receiving and holding a part of the spring remote from the portion thereof engaging the spindle against displacement with said portion by the spindle.

10 In testimony whereof I affix my signature.
JOHN W. STEWARD.
